UNITED STATES PATENT OFFICE

115,770

DESIGN FOR A SHADE HOLDER

Leon Spero, East Cleveland, Ohio

Application May 6, 1939, Serial No. 84,829

Term of patent 7 years

To all whom it may concern:

Be it known that I, Leon Spero, a citizen of the United States, residing at 1304 Eddy Road, in the city of East Cleveland, county of Cuyahoga, and State of Ohio, have invented a new, original, and ornamental Design for a Shade Holder, of which the following is a specification, reference being had to the accompanying drawing, forming a part thereof.

I claim:

The ornamental design for a shade holder, substantially as shown.

LEON SPERO.
